UNITED STATES PATENT OFFICE.

ELIZABETH CALKINS, OF ST. JOSEPH, MISSOURI.

MATTRESS-HOLDER FOR BEDS.

SPECIFICATION forming part of Letters Patent No. 551,259, dated December 10, 1895.

Application filed September 4, 1895. Serial No. 561,441. (No model.)

To all whom it may concern.

Be it known that I, ELIZABETH CALKINS, of St. Joseph, in the county of Buchanan and State of Missouri, have invented certain new and useful Improvements in Mattress-Holders for Beds, of which the following is a full, clear, and exact description.

This invention relates to certain improvements in mattress-holding devices, such as are designed for use in connection with folding beds for holding the mattress, bedding, &c., in place when the bed is turned up or folded, and the object of the invention is to provide a device of this character of a simple and inexpensive construction, adapted to be applied to beds of all kinds, and adjustable so as to be adapted to hold mattresses and bedding of different thicknesses.

The invention consists in a mattress-holder adapted to be attached to a bed-rail, and having jaws arranged to engage the upper and lower sides of the bedding so as to securely hold the same in place.

The invention also contemplates certain novel features of the construction, combination, and arrangement of the various parts of the device, whereby certain important advantages are attained and the device is made simpler, cheaper, and otherwise better adapted and more convenient for use than various other similar devices heretofore employed, all as will be hereinafter fully set forth.

The novel features of the invention will be carefully defined in the claims.

Reference is to be had to the accompanying drawings, forming a part of this specification, in which similar characters of reference indicate corresponding parts in both the figures.

Figure 1 is a view drawn to a small scale and showing a fragment of a mattress and a bed-rail, having my improved bedding-holder in position for use; and Fig. 2 is a perspective view showing the holder detached and on an enlarged scale.

In the views 1 represents the rail, usually the foot-rail, of a folding bed to which my improved bedding-holder is applied, and 2 represents the mattress or bedding, there being, as clearly shown in Fig. 1, two of said holders employed, one near each end of the said foot-rail, held in place by means of screw-eyes 3, screwed in the foot-rail.

The bedding or mattress holder comprises two sections 4 and 5, arranged to fit flat against each other, as clearly seen in Fig. 2, the section 4 being provided with a longitudinal slot 6, and the section 5 being provided with a projecting lug 7 arranged to play therein, said lug having an elongated or flattened head, as clearly shown, so arranged that when said sections 4 and 5 are aligned they will be locked together, but when set at right angles to each other said sections may be separated. Each section 4 and 5 is provided at its outer end with a bent portion or arm 8, having at its extremity a head or enlargement 9, and said bent ends 8 are bent or curved toward each other so that the heads 9 stand in position to engage the upper and lower surfaces of the mattress 2 or other bedding, so as to clamp the same securely between them.

To the end of section 4 of the device is pivoted, as clearly seen at 10 in Fig. 2, a locking or latch plate 11, having a series of notches 12 formed in one side, adapted when said plate is swung on its pivotal point 10 to engage the flattened head of lug 7, and hold the same against movement longitudinally of the slot 6, as will be readily understood.

In operation, the sections 4 and 5 of the device being held by the screw-eye 3 or equivalent device in the foot-rail 1 of the bed are opened by disengaging the locking-plate 11 from the head of lug 7, and the heads 9 are pressed firmly against opposite sides of the mattress or bedding 2, after which the said locking-plate 11 is swung on its pivot so as to engage one of its notches 12 with the head of lug 7 and thus hold the sections of the device securely in position. When the mattress or bedding is thus clamped in the bed-frame, it is evident that the said frame may be turned up or folded without any danger of the bedding falling out of place, whereby a very annoying disadvantage of folding beds is overcome. The eye 3 on the rail 1 also acts to prevent the locking-plate 11 from becoming disengaged from the lug 7 when the device is in use, as will be readily understood.

The device constructed as above described is of an extremely simple and inexpensive character and is well adapted for the purposes for which it is intended, since it is compact and adjustable to bedding of various thick-

nesses and is very durable. It will also be obvious that the device is susceptible of considerable modification without material departure from the principles of my invention, and for this reason I do not wish to be understood as limiting myself to the exact form of the device herein set forth.

Having thus fully described my invention, I claim as new and desire to secure by Letters Patent—

1. A bedding holder comprising two sections each having an arm projecting at angles from one end, one of said sections being provided with a longitudinal slot and the other with a projecting lug arranged to engage and slide along said slot, and means for locking said sections adjustably together, substantially as set forth.

2. A bedding holder comprising two sections each having an arm projecting from one end, one section having a longitudinal slot and the other section having a projecting lug arranged to engage and slide along said slot, and a locking plate carried on the slotted section and arranged to engage the lug on the other section to lock the sections together, substantially as set forth.

3. A bedding holder comprising two sections each having an arm projecting from one end, one section having a longitudinal slot and the other section having a projecting lug arranged to engage and slide along said slot, and a locking plate pivoted on the slotted section and having a series of notches arranged to engage the lug on the other section, to lock the sections adjustably together, substantially as set forth.

4. A bedding holder comprising two sections each having an arm projecting from one end, one section having a lug and the other having a pivoted notched locking plate to engage said lug and hold the sections adjustably locked together, and a fastening device for securing the holder to the bed rail, said device having an eye to receive the sections and also to receive said locking plate to hold the same against pivotal movement when the said locking plate is engaged with said lug, substantially as set forth.

ELIZABETH CAULKINS.
